UNITED STATES PATENT OFFICE.

JOHN STEMBER, OF NEW YORK, N. Y.

DESIGN FOR A BODY PORTION FOR BELTS.

SPECIFICATION forming part of Design No. 32,805, dated June 5, 1900.

Application filed May 10, 1900. Serial No. 16,229. Term of patent 3½ years.

To all whom it may concern:

Be it known that I, JOHN STEMBER, a citizen of the United States, residing at New York, in the borough of Manhattan and State of New York, have invented and produced a new and original Design for Body Portions for Belts, of which the following is a specification, reference being had to the accompanying drawings, forming part thereof.

Figure 1 is an elevation of a body portion of a belt, showing my new design; and Fig. 2 is a transverse section thereof, taken on the line 2 2 of Fig. 1.

As shown in the drawings, the leading or material feature of my design consists of a central ornament A in the form of a square or reef knot, from which extend on opposite sides converging strands B B'. At the junc-

ture of the ornamental-knot portion with the strands B B' outward-bulging swells C are 20 formed, the ends of the strands B B' terminating with the ends of the body portion of the belt. The ornamental knot A and the continuations or strands B B' are embossed, as shown, so as to simulate a rope. 25

What I claim is—

The design for a body portion for belts, as herein shown and described.

In testimony that I claim the foregoing as my invention I have signed my name in presence of two subscribing witnesses. 30

JOHN STEMBER.

Witnesses:

PAUL GOEPEL,
GEO. L. WHEELOCK.
